J. F. CALLAHAN

HEMOSTATIC FORCEPS

Filed Feb. 18, 1921

UNITED STATES PATENT OFFICE.

JOHN F. CALLAHAN, OF BROCKTON, MASSACHUSETTS.

HEMOSTATIC FORCEPS.

Application filed February 18, 1921. Serial No. 445,949.

To all whom it may concern:

Be it known that I, JOHN F. CALLAHAN, a citizen of the United States, residing at Brockton, in the county of Plymouth and 5 State of Massachusetts, have invented new and useful Improvements in Hemostatic Forceps, of which the following is a specification.

The invention about to be described relates to forceps for closing arteries, veins, blood vessels and other bleeding points in the course of surgical operations preparatory to tying a ligature about the said bleeding portions.

15 My object has been to provide forceps of this character with means for so holding a ligature prepared for tying, and means for so holding the bleeding tissue, as to make certain that the ligature, when tied, will surround the artery, or other vessel or part from which blood flows, so deeply and at such a distance back from the end of the artery, or surface of the bleeding tissue, that the ligature will not be liable to slip off.

20 Many situations occur in surgery where an artery or blood vessel is severed and is so difficult of access that a ligature cannot be passed about the bleeding point without extreme difficulty, and then when tied the ligature is insecure. In some cases it has been impossible to ligate the bleeding point at all. The last statement is particularly true of tonsilectomy; in which arteries are severed, but the area of the tonsil fossa is 25 so small and its depth so great, and the throat cavity is so restricted, that the surgeon cannot pass the loop of a ligature over the end of an ordinary hemostatic forceps which has been closed on a bleeding point, and make it secure.

In carrying out my object, above stated, I have devised a forceps by which the tissue surrounding the blood tube, or around any other bleeding point, may be grasped, 45 however difficult of access the bleeding point may be; and have equipped such forceps with means for holding a ligature ready to be tied in a loop about the bleeding point, and particularly with means for so grasping the tissue and guiding the ligature that the latter may be tied tightly and in such a manner as to compress a narrow neck of the tissue below the original surface thereof before the forceps need to be released.

50 For a complete explanation of the inven-

tion and its utility, attention is called to the drawings forming a part of this specification, in which,—

Figure 1 is an elevation showing one side of a particular forceps embodying the invention.

Figure 2 is a longitudinal sectional view between the jaws and handles of the forceps taken on line 2—2 of Figure 1.

Figure 3 is a detail sectional view taken on line 3—3 of Figure 2.

Figure 4 is an elevation showing the opposite side of the forceps from that shown in Figure 1.

Figure 5 is a perspective view of the jaws of the forceps in open position.

Figure 6 is an elevation showing the jaws in their closed position and as seen from the view point of Figure 4.

Figure 7 is an elevation taken similar to Figure 6, but showing the ligature drawn tight about the tissue in the grasp of the forceps.

Figure 8 is an elevation of the jaws seen from the view point of Figure 1, but represented as being closed.

Figure 9 is a view of one of the jaws similar to that shown in Figure 2, illustrating the manner in which the ligature is tied about the tissue while the latter is grasped by the jaws.

Figure 10 is a cross section taken on line 10—10 of Figure 7 illustrating the ligating operation.

Figure 11 is a side view of a completed ligature.

Like reference characters indicate the same parts wherever they occur in all the figures.

The forceps consist of two members 12 and 13 crossing one another and pivoted together by a pivot screw 14 in the manner common to forceps of various types. The jaws 15 and 16 are extensions of the members 12 and 13 respectively, and said members have loops or rings 17 and 18 to receive the thumb and finger of the operator. The arms or handle parts of the forceps members carry complementary latching teeth adapted to be interengaged when the jaws are closed, there being one tooth 19 on the handle part of the member 12 and a series of teeth 20 on the handle part of member 13. Preferably the members 12 and 13, between the pivot and the finger

holds, are long and springy in order that they may be latched in the closed position, even though the jaws remain more or less spread apart by the mass of interposed tissue.

In the face of each jaw and opening toward the side of the forceps which is exposed to view in Figures 4, 6 and 7, is a recess 21. This recess does not extend to the 10 extremity of the jaw nor does it extend all the way across the face of the jaw but leaves a gripping surface which is the full width of the jaw in the part 22 and is flanked by a part 23 of less than the full width. This 15 surface may be corrugated or otherwise roughened to increase its gripping power. Between the parts 22 and 23 in the face of each jaw is a groove or notch 24 wide and deep enough to receive a ligature. This 20 groove or notch 24 merges into the recess 21. There is a guard wing or lug 25 projecting from that edge of each jaw which is exposed to view in Figure 4 and located beside the recess 21. The purpose of this 25 guard is to prevent the thread or cord which passes along the side of the jaw and through the groove 24 from slipping into the recess, wherefor the guard is given a 30 shape and dimensions appropriate to achieve this result.

On the outer face of the member 13 is mounted a clamp or gripper 26, the purpose of which is to hold the loop or bight of the cord to be used as a ligature. This 35 clamp is made as a stiff spring bar which is fastened at one end by a screw 27 to the member 13, and the free end of which is shaped and arranged to bear against the surface of this member when the jaws are 40 opened. Preferably a notch 28 is formed in the inner face of the clamp to receive the cord. A pin 29 is secured to the clamp and passes thence freely through a hole in the member 13 and into contact with a cam 45 or wedging surface 30, shown in Figure 3, formed in the adjacent face of the member 12, the arrangement and form of which is such that when the jaws are closed this surface wedges the pin outward and separates 50 the clamp from the member 13, while when the jaws are opened the recession of the cam surface allows the clamp to close against the member 13. The separating movement thus given the clamp is great 55 enough to permit the ligature cord to be readily slipped into and out of the space between the clamp and the opposing surface of the member 13. The pin 29 is essentially a part of the clamp which engages 60 the cam surface, and its function is that of a pusher for opening the clamp when the jaws are closed.

A clip or retainer 31 is mounted on the outer side of the member 12 to hold the ligature cord, and a similar clip may be

mounted in a similar manner on the outer side of the other member for holding the other end of the cord; although the latter clip is not shown, and indeed, the clip 31 may be omitted without destroying the 70 utility of the instrument.

A spring wire 32 is anchored at its end 75 33 to the member 13 and is restrained from free movement by an abutment stud 34. Its free end 35 bears against the member 12 80 and tends to open the forceps, holding the jaws open when the handle parts of the instrument are unlatched.

In using the forceps for the purposes set forth, it is first threaded with the thread 85 or cord to be used as a ligature. Such cord may be of silk, catgut, horsehair or any other material indicated in surgical practice as suitable for ligatures and sutures. To thread the forceps, the jaws and handles 90 are first closed together, which opens the clamp 26. Then the middle part *a* of the cord is slipped under the clamp and the jaws are opened, whereby the clamp is caused to grip the cord. Then the cord, at 95 one side of the gripping point, is passed along the face of the jaw 16, which is exposed to view in Figure 4, outside of the guard 25, through the groove 24 in that jaw and along the opposite side of the instrument to the clip 31, by which it is held as shown in Figure 1. The other part of the 100 cord is then passed along the jaw 15, outside of the guard 25, and through the groove 24 in that jaw and along the handle part of the member 13, where it may be held either by a clip or by the fingers of the operator while grasping the forceps, or it may be allowed to hang free.

The cord is now clear of the gripping 105 faces of the jaws and is so placed that it does not interfere in any way with the use of the instrument in the ordinary way as a hemostat, and it may be used to grip the end of a severed blood tube or any other 110 bleeding point in the tonsil fossa, or any other part of the anatomy exposed in the course of a surgical operation.

Of course the instrument, or any part thereof, may be made as large or as small as 115 may be needed in any circumstances, whereby its use as a hemostat at points most difficult of access is made possible.

Before the jaws are closed upon the bleeding point they may be pressed into the surrounding soft tissue far enough to secure a deep bite, and when closed they are locked by the latch teeth 19 and 20, leaving the operator free to use both hands for tying the ligature. The closing of the jaws also opens the clamp 26 and leaves the loop of the cord free to be drawn tight about the gripped tissue; and the grooves 24 furnish runways through which the cord may be drawn and by which the loop is securely guided to po- 120 125 130

sition about this tissue, even though the ends of the cord are grasped by the operator at a long distance from the bleeding point.

Figures 6 to 11 illustrate the manner in which the tissue at the bleeding point is gripped by the forceps and the steps of tying the ligature. In Figure 6 the tissue has just been grasped and the loop of the cord released. Figure 7 shows the same view of the jaws after the loop has been drawn tight. Figure 8 shows the manner in which the knot is tied and is drawn tight against the tissue. Figures 9 and 10 show the manner in which the knotted loop is enabled by the formation of the jaws to compress the tissue where the ligature is applied, leaving the part of the tissue in front of the ligature as an enlarged head which prevents the ligature from slipping off; and Figure 11 shows the completed ligature.

In these figures 36 represents any part of the body tissue from which hemorrhage occurs, and 37 represents the part which is gripped by the jaws. The forceps are indented into the tissue far enough to cause this gripped part to cross the grooves 24. Then the effective gripping surfaces of the jaws are their terminal faces 22 and the parts 23 beside the cavities 21. That part of the mass of tissue which lies over the cavities is left free, wherefore the loop of the ligature is enabled to compress that part of the tissue at the bottom of the cavities and to leave uncompressed the extremity of the gripped mass. The knot may be tied and the loop drawn tight while the forceps remain closed upon the tissue, because the loop is entirely contained in spaces within the jaws. Then after the tying of the ligature has been completed the forceps may be removed. Provided a deep enough bite of the tissue has been taken in the first place (which is always possible) the extremity of the gripped mass is enabled to expand after removal of the forceps and to form an enlarged head above the narrow neck where the ligature is applied, which head retains the ligature in place.

This entire operation can be performed without need of the operator bringing his fingers near the bleeding point and is thus capable of being carried out with respect to bleeding points in the tonsil fossa and other spots which cannot be reached by the operator's fingers.

What I claim and desire to secure by Letters Patent is:

1. Hemostatic forceps having gripping jaws, and such jaws being provided with runways in their gripping faces adjacent to but back from the extremities of the jaws, said runways being adapted to contain a ligature cord and to guide a loop formed in such a cord to the substance gripped between the jaws.

2. Hemostatic forceps having gripping jaws with runways in their opposing faces and means for temporarily retaining at a point distant from the ends of such jaws the loop of a cord passing through said runways.

3. Hemostatic forceps having gripping jaws with runways, means for temporarily retaining at a point distant from the ends of such jaws the loop of a cord passing through said runways, and means for releasing said retaining means when the jaws are closed.

4. Hemostatic forceps comprising jaws having terminal gripping faces and adjacent gripping faces of less width than the terminal faces and runways for a ligature cord between said terminal and adjacent faces, whereby the ligature contained in said runways is enabled to be drawn tight about the tissue grasped between the jaws and to compress said tissue into a narrow neck as to that part about which the ligature is passed.

5. Hemostatic forceps comprising pivoted jaws and connecting handle members, said jaws having opposed gripping surfaces at their terminals, cavities opening at the sides of the jaws adjacent to said terminals, and runways opening from said cavities between said terminals and the jaw faces beside the cavities.

6. Hemostatic forceps comprising pivoted jaws and connecting handle members, said jaws having opposed gripping surfaces at their terminals, cavities adjacent to the terminals, runways opening from said cavities opening at one side of the jaws and extending part way across the jaws between said terminals and the jaw faces beside the cavities, and temporary clamping means on the same side of the forceps as that toward which said cavities open, adapted to hold the loop of a cord passing through the runways.

7. Hemostatic forceps comprising pivoted jaws and connecting handle members, said jaws having opposed gripping surfaces at their terminals, cavities opening at the side of the jaws adjacent to the terminals, runways opening from said cavities between said terminals and the jaw faces beside the cavities, guards arranged on the jaws adjacent to the outer boundaries of said cavities in position to guide a cord passing through said runways outside of the mouths of said cavities and along the adjacent sides of the jaws, and means for holding the loop or bight of a cord so disposed.

8. Hemostatic forceps comprising complementary jaws having gripping faces and provided with guiding means for leading a cord from one side to the opposite side of said jaws, combined with a holder adapted to retain the loop of a cord engaged with said guiding means.

9. Hemostatic forceps comprising complementary gripping jaws, each of said jaws having a guideway in which a ligature cord is adapted to be placed, combined with temporary holding means for the loop of a cord, such holding means being arranged at one side of the forceps.
10. Hemostatic forceps comprising complementary gripping jaws and handle members operable to open and close said jaws together, the forceps also having at one side a cord holder, and each of the jaws having a guideway adjacent to its extremity adapted to receive the parts of a cord running from 15 said holder to the side of the forceps opposite thereto.
11. Hemostatic forceps comprising combined jaws and handle members pivoted together, a clamp carried by one of said members adjacent to the pivot point and normally arranged to press against the adjacent member, and a cam portion carried by the other member arranged to act upon said clamp to separate it from the adjacent member 25 when the jaws are closed, said jaws having transverse runways opening in their gripping faces.
12. Hemostatic forceps comprising complementary jaws having at their extremities 30 gripping surfaces of a certain width, and

having gripping faces of less width back from such extremities, said jaws also having runways opening in said faces of less width.

13. Hemostatic forceps comprising complementary jaws having at their extremities gripping surfaces of a certain width, and having gripping faces of less width back from such extremities, said jaws also having runways opening in said faces of less 35 width, and a clamp arranged to hold the bight of a cord in such a position that the sides of said bight may extend from said clamp and through said runways.

14. Hemostatic forceps comprising complementary jaws having at their extremities gripping surfaces of a certain width, and gripping faces of less width back from such extremities, said jaws also having runways opening in said faces of less width, a clamp 40 arranged to hold the bight of a cord in such a position that the sides of said bight may extend from said clamp and through said runways, and means for opening said clamp when the jaws are closed, the clamp being 45 closed when the jaws are opened.

In testimony whereof I have affixed my signature.

JOHN F. CALLAHAN.
